Fig. 1

Fig. 5

FIG. 3

FIG. 4

FIG. 2

Fig. 1 is a perspective view of a tire showing my new design, it being understood that the tread portion shown is repeated throughout the circumference of the tire and that the shoulder design shown is repeated throughout the circumference of the shoulder, the opposite side of the tire being substantially like the side shown;

Fig. 2 is an enlarged fragmentary plan view of the tread portion of the tire shown in Fig. 1;

Fig. 3 is a sectional view through the tire taken substantially on the plane indicated by the line 3—3 of Fig. 2;

Fig. 4 is an enlarged fragmentary side elevational view of the tire; and

Fig. 5 is a fragmentary sectional view to an enlarged scale through one of the radial shoulder ribs, the view being taken substantially on the plane indicated by the line 5—5 in Fig. 4.

I claim:

The ornamental design for a tire, substantially as shown and described.
